G. M. FRANKS.
DISPLAY DEVICE.
APPLICATION FILED MAR. 2, 1921.

1,422,845.

Patented July 18, 1922.

Inventor:
Geo. M. Franks.
By: Franklin,
his Attorney.

UNITED STATES PATENT OFFICE.

GEORGE M. FRANKS, OF ST. PAUL, MINNESOTA.

DISPLAY DEVICE.

1,422,845.

Specification of Letters Patent. Patented July 18, 1922.

Application filed March 2, 1921. Serial No. 449,183.

To all whom it may concern:

Be it known that I, GEORGE M. FRANKS, a citizen of the United States, residing at St. Paul, in the county of Ramsey and State of Minnesota, have invented a new and useful Improvement in Display Devices, of which the following is a specification.

My invention relates to display stands for displaying merchandise, particularly of the 10 type in which the merchandise is mounted on a card, and has for its object to provide a stand which may be made out of sheet metal pressed into the desired shape to hold the cards in removable position upon the same.

15 In carrying out the objects of my invention I provide corner, base and top members each formed of a single piece of sheet metal pressed into the desired shape with means for holding the cards and means for locking 20 the members together.

The full objects and advantages of my invention will appear in connection with the detailed description thereof and are particularly pointed out in the claims.

25 In the drawings, illustrating the application of my invention in one form:—

Fig. 1 is a side elevational view of my invention.

Fig. 2 is a plan view of the bottom frame 30 member of my invention.

Fig. 3 is a plan view of the top frame member.

Fig. 4 is a plan sectional view taken on line 4—4 of Figure 1.

35 Fig. 5 is a sectional elevational view taken on line 5—5 of Figure 4.

Fig. 6 is a detail sectional view taken on line 6—6 of Figure 5.

40 Fig. 7 is a detail sectional view taken on line 7—7 of Figure 1.

My stand comprises primarily a base member 10 formed of a single piece of sheet metal substantially square in configuration at the corners of which are mounted four 45 uprights 11 which are held in spaced relation to each other at the tops by means of an upper frame member 12. A rod 13 passes directly through both the frame member 12 and the frame member 10 and is screwed into 50 a circular base 14 on which the entire device is supported. A nut 15 screwed on the end of this rod serves to hold the parts clamped against the base 14 to form a rigid structure.

55 The uprights 11 are constructed so as to form two side members 16 and 17 connected by an oblique back 18. These uprights are

supported on the exterior of the frame member 10 as follows. Along the perimeter of frame member 10 the edges 19 thereof are turned up to form flanges extending substantially around the device. At the corner of each of these flanges 19 is pressed outwardly from the metal thereof a pair of ears 20 and 21 which are spaced from said flanges 19 so as to form a socketed seat in which the 60 uprights 11 may be placed. One of these uprights is shown in cross section as being mounted on said ears in Figure 2. To stiffen the member 10, I form the same in the shape of a cross, with arms 22 and 23 which 65 are provided at their edges with the ribs 24. As pressure is exerted upon the device through the rod 13, ribs 24 and the arms 23 and 22 hold the uprights 11 in proper position upon the frame member 10. 70

75 The manner of attachment of the upper frame member 12 to the device is best shown in Figures 3, 4, 5 and 6. Member 12 is shaped in the form of a star having four protruding points or members 25, 26, 27 and 28, each of which is formed with ribs 29 along the edges thereof for stiffening said member to make the same rigid. At the end of each of arms 25, 26, 27 and 28 I provide a depending tongue 30 which is adapted to slip 80 in between lip 31 formed at the top of each of the uprights 11 and the back portion 18 of said uprights. The lip 31 is formed by pressing a band of metal of the uprights 11 inwardly as indicated in Figure 4 to leave a 85 space between the back 18 of the uprights 11 and lip 31 in which the tongue 30 may be inserted. When the device is assembled as indicated in Figure 1 the rod 13 presses the members 12 and 10 towards each other causing tongues 30 and the ears 20 and 21 to become snugly seated at the ends of the uprights 11 thereby holding the device in place. A washer 32 mounted on rod 13 between 90 frame 10 and the base 14 permits the entire 100 stand to be rotated relative to said base 14 to display successively the goods mounted on the four sides of the device. 95

105 The means for holding the goods comprises a plurality of cards 33 which have the goods secured to the same, which cards are adapted to slide in back of the side members 16 and 17 of the uprights 11 and which are held in place upon the said guides by means of a number of ears 34 which are pressed inwardly from the metal as indicated in Figure 7 at 35, to form a space between said 110

22
 lugs and the portions 16 and 17 of said uprights. In Figure 7 one of the cards is shown positioned between a lug 34 and the member 17 of the upright 11. At the bottom 5 of the device the cards 33 are supported by member 10 in a space 36 formed on the bottom of the body portion thereof between the flanges 19 and a number of upturned wings 37 which are best shown in Figures 1 and 10 2. The flanges 19 and said wings 37 hold the card from movement while the bottom of frame member 10 furnishes the necessary support for carrying the said card and the goods attached thereto.

15 To prevent the device from overturning, base 14 is constructed so as to have sufficient weight to hold the device in place after the same has had the goods and the cards mounted thereon. If desired, the entire base 20 may be constructed of cast iron or some other metal suitably heavy enough to serve the purpose. In the drawings, however, I have shown a type of base which may be constructed of sheet metal to serve the same 25 purpose. This base comprises an outer shell 40 pressed into the desired shape which has a downwardly projecting boss 41 into which the rod 13 may be screwed. The extreme edges of shell 40 are turned inwardly at 141 30 and the entire base is filled with a substance such as concrete or some other suitable composition as indicated at 42. The function of the inturned edge 141 of shell 40 is to cause the filler member 42 to be held in position 35 within the shell 40. This construction may be more cheaply produced than the solid cast iron base and still serves the same purpose.

The advantages of my invention are manifest. The device can be constructed from 40 sheet metal pressed into the desired shape so as to be constructed at a trivial cost. The device is collapsible and may be packed in a small container so as to be easily conveyed through the mails. When the entire 45 stand is erected the same has a very attractive appearance and displays the maximum amount of goods in a limited space. The stand is so designed as to be placed on a counter or table where the same may readily be seen by the public.

In accordance with the patent statutes I have described the principles of operation of my invention, together with the apparatus which I now consider to represent the 55 best embodiment thereof, but I desire to have it understood that the construction shown is only illustrative and that the invention can be carried out by other means and applied to uses other than those above 60 set forth within the scope of the following claims:

I claim:

1. A card holding display device comprising a frame member formed of a single 85 piece of sheet metal, having flanges turned

up along all of the edges thereof, complementary flanges extending partially along said first named flanges in spaced relation thereto being turned up from the body of said frame member to form a number of 70 grooves, and means secured to said frame member and cooperating with said grooves to support a plurality of cards.

2. A display stand comprising an upper and a lower frame member, ears formed on 75 said lower frame member and a plurality of uprights mounted on said frame members held in place thereon by means of said ears and means for clamping said frame members together.

3. A display device comprising a lower frame member formed of a single piece of sheet iron, flanges turned upwardly from the body of said lower frame member along the edges thereof, ears pressed out of said 85 upturned flanges and uprights mounted on said lower frame member between said ears and flanges.

4. A display stand comprising a lower frame member, a plurality of ears formed 90 on said lower frame member and spaced therefrom, a plurality of uprights mounted on said frame member and positioned between said frame member and ears and supported thereon and means for clamping said 95 uprights in place upon said lower frame member.

5. A display stand comprising an angular body portion having a plurality of uprights arranged at the corners thereof, 100 flanges formed on said uprights extending towards similar flanges on adjacent uprights, pairs of said flanges lying in intersecting planes, ears formed on said uprights lying in planes parallel to said flange planes to 105 hold a plurality of cards against the said flanges.

6. A display device comprising a lower frame member formed of a single piece of sheet iron having a flange turned upwardly 110 at the edge thereof, a second flange extending partly across said lower frame member parallel to said first flange in spaced relation thereto being turned up from the body of said lower frame member to form grooves 115 and a plurality of uprights mounted on said lower frame member, having card holding means lying in the same plane as said grooves.

7. A display device comprising a lower 120 frame member formed of a single piece of sheet iron, having a flange turned upwardly at the edge thereof, a second flange extending partly across said lower frame member parallel to said first flange in spaced relation 125 thereto being turned up from the body of said lower frame member to form grooves, a plurality of uprights formed of sheet metal supported on said lower frame member, and ears pressed inwardly from the 130

metal of said uprights in spaced relation thereto to form grooves lying in the plane of said frame member grooves.

8. A display stand comprising a body portion having a plurality of uprights, said uprights having flanges turned at right angles to each other and sets of ears formed on each of the flanges of said uprights and positioned in spaced relation thereto.

9. A display stand comprising a body portion, having a plurality of uprights each formed of a single piece of material bent with two flanges issuing outwardly at right angles from one another and card holding means formed on each of the flanges of said uprights, said means being adapted to hold a number of cards along said flanges.

GEORGE M. FRANKS.
